UNITED STATES PATENT OFFICE.

ERASTUS E. WINKLEY, OF LYNN, MASSACHUSETTS.

BOTTLE FILLING AND CAPPING MACHINE.

1,216,036.

Specification of Letters Patent. Patented Feb. 13, 1917.

Application filed February 16, 1914. Serial No. 818,970.

To all whom it may concern:

Be it known that I, ERASTUS E. WINKLEY, a citizen of the United States, residing at Lynn, in the county of Essex and State of Massachusetts, have invented certain new and useful Improvements in Bottle Filling and Capping Machines; and I do hereby declare the following to be a full, clear, and exact description of the invention, such as will enable others skilled in the art to which it appertains to make and use the same.

The present invention relates to machines for filling and capping bottles which are used in various industries to package beverages, such, for instance, as beer, milk, water and tonic.

Heretofore it has been customary to locate a filling machine beside a capping machine and to operate these machines entirely independently of one another. It often happens in operating these machines that one or both of them become jammed or clogged with work or fails to operate in a proper manner. When this occurs, unless there is an operator or attendant for both machines, and steps can be taken immediately to remedy the difficulty, one or both of the machines is liable to be injured or develop conditions which are likely to destroy the bottles and waste their contents.

One of the objects of the present invention is to produce a novel machine for filling and capping bottles which will automatically stop operating in case the machine or mechanism becomes clogged or jammed, or for any other reason unusual resistance is offered to the movement of the driven parts, or conditions are developed dangerous to the bottles.

To the accomplishment of this object a feature of the invention contemplates the provision, in a filling and capping machine provided with mechanism for filling bottles, and mechanism for capping the filled bottles, of means for stopping the machine when an overload or unsafe conditions occur during its operation.

Broadly considered the machine may be stopped when an overload or unsafe conditions occur during the operation of either the filling or capping mechanisms, or both. As an overload usually occurs only in the filling mechanism, and as unsafe conditions are ordinarily developed in the capping

mechanism, I prefer to stop the machine when an overload occurs in the filling mechanism and when unsafe conditions occur in the capping mechanism.

The manner of stopping the machine under an overload in the filling mechanism may take any form found desirable or expedient. It is preferred, however, to stop the filling mechanism upon the development of the overload and permit the capping mechanism to continue to operate for an interval after the stopping of the filling mechanism. This manner of stopping the machine forms an important feature of the invention as it permits the filling mechanism to be stopped immediately, while the capping mechanism may overrun until the inertia of its comparatively heavy and rapidly-moving parts is exhausted.

Other features of the present invention consist in a timing shaft for connecting the filling and capping mechanisms and controlling their times of operation, in a novel construction for varying the speed of the timing shaft to permit the machine to fill and cap either pint or quart bottles, in a novel construction for permitting the manual introduction of stray filled bottles upon the runway between the filling and capping mechanisms, in improved devices for restoring the timed operating relation of the filling and capping mechanisms after the filling mechanism has stopped under an overload, in a novel stop mechanism, and in certain devices, combinations and arrangements of parts tending to improve and simplify the operations of filling and capping machines and to enable them to operate with certainty at a high rate of speed and without liability of breakage of parts. The advantages of these devices, combinations and arrangements of parts will be obvious to those skilled in the art from the following description.

The various features of the present invention will be best understood from an inspection of the accompanying drawings illustrating the preferred embodiment of the invention, in which,

Fig. 17 is a detail front elevation of the devices for stopping the machine when an obstruction is found upon one of the bottle supports of the capping mechanism; and

Fig. 18 is a detail side elevation of the devices shown in Fig. 17.

The main features of the preferred form of the invention may be briefly described 40 as follows:

The machine is provided with mechanism for filling bottles and with mechanism for capping the filled bottles. The bottles are fed into the filling mechanism where they 45 are filled with liquid and then discharged into a runway leading to the capping mechanism which automatically takes the filled bottles, one at a time, from the runway, places the caps thereon, and automatically 50 discharges the capped bottles from the machine. Whenever the filling mechanism is jammed, or fails to operate properly, or is otherwise overloaded, or unsafe operating conditions occur during the operation of 55 the capping mechanism, the machine is automatically stopped to prevent breakage to the bottles or to the machine. The devices for stopping the machine under an overload on the filling mechanism are constructed to permit the capping mechanism 60 to continue to operate, if necessary, a short time after the filling mechanism has stopped so that the working parts of the capping mechanism may be brought into a predetermined position.

In the embodiment of the invention illustrated in the drawings the bottles to be filled and capped are loaded, one by one, upon a series of bottle supports 1, herein shown as thirty-two in number, carried by a continuously rotating carrier 2, at a loading station marked L. S., (Fig. 2). During a single rotation of the carrier each bottle is first filled with beer and then discharged at a discharging station marked D. S., (Fig. 2), for conveyance to the capping mechanism.

Each support 1 and its associated bottle engaging arms 3 project laterally from a sleeve 4 secured to a plunger 5, (Fig. 1). The plunger 5 is mounted to slide vertically in lugs 6 and 7 formed upon spiders 8 and 9 carried by the carrier 2, (Fig. 1).

Associated with each bottle support is a filling head 10 (Figs. 1 and 7), projecting from the bottom of a drum 11, which is supported by the carrier 2. The drum 11 is provided with a track 12 engaged by rolls 13 carried by vertical rods 14 on the machine frame. The beer for the bottles flows to the drum 11 through a pipe 14, (Fig. 1). From the drum 11 the beer flows through the thirty-two heads 10 and then through tubes 15 arranged to enter the bottles through their mouths. The flow of beer from each head into its associated tube 15 is controlled by a valve mechanism 16, (Figs. 1 and 7), pivotally mounted on the head. This valve mechanism is held locked in closed position by a dog 17, (Fig. 1), normally arranged to engage the lower end of a trip 18 which is pivotally mounted on the valve mechanism 16. The trip 18 is forcibly held in contact with the dog 17 by a spring 19 coiled around the pivot of the trip and having one end secured to the valve mechanism 16 and its other end engaged with a pin 20 on the upper arm of the trip. The dog 17 is slidably mounted on the tube 15 and is normally held in position to engage the trip 18 by a spring 21 coiled around the tube 15 and interposed between the filling head and a shoulder 22 on the dog.

During the rotation of the carrier 2 each bottle is first elevated to position its associated tube 15 within the bottle. This movement of the bottle also lifts the dog 17 out of engagement with the trip 18. The trip 18 is then swung about its pivot by the spring 19 which positions the upper end 23 of the trip for engagement with a block 24, (Figs. 1, 2, 7 and 8), on a ring 25 carried by the rods 14, which strikes the upper end of the trip and swings the trip and the valve mechanism 16 into position A, (Fig. 7). The valve is now open and the beer flows down the tube 15 into the bottle. The beer continues to flow until the bottle is filled at which time the lower end of the

trip 18 is struck by a second block 26 on the ring 25 which causes the valve to be closed and the flow of beer into that particular bottle to be stopped, position B, Fig. 7. The filled bottle is then lowered into a position of clearance and is there discharged at the discharging station. Just before an empty bottle is loaded on the support now empty, a third block 27 on the 10 ring 25 tips the trip backwardly against the tension of its spring 19 so that the dog 17 may again engage and lock the trip in its original position. This completes the cycle of operation of the actual filling mechanism.

The bottle is elevated against the dog 17 by a coiled spring 28, (Fig. 1), one end of which is connected to the lower end of the plunger 5 and the other end of which is connected to the spider 8. In order to lock the bottle from lowering under the weight or pressure of the flowing beer and to press the mouth of the bottle against the packing (which is of usual form in machines of this class) in the filling head, the rods 14 carry a circular track 29, (Figs. 1 and 7), which support a series of rolls 30, (Figs. 7, 9 and 10), which travel over the track during the rotation of the bottle supports. Each roll 30 is journaled upon a pin 31 projecting from a block 32 loosely surrounding a rectangular portion of the plunger 5. With this construction the plunger 5 slides freely through the block 32 as the bottle support is raised under the influence of the spring 28. After the bottle mouth has disengaged the dog 17 from the trip 18 the block 32 and plunger 5 are clutched together in order that the bottle may be locked in its elevated position. To clutch the plunger 5 to the block 32 the block is provided with a frustoconical opening 33 which contains four rolls 34. The rolls 34 are normally held out of gripping position by a spring 35, coiled 45 around the plunger 5 and interposed between the lug 7 and the top of the block 32, which depresses the block 32 so that bars 36 carried by a collar 37 on the plunger 5 lift the rolls out of gripping position, (Fig. 50 9). As soon, however, as the roll 30 reaches an incline 38, (Fig. 7), on the track 29, the rolls are lifted clear of the bars 36 as the block 32 is elevated thus permitting the rolls 34 to become jammed between the block 32 55 and the plunger 5. The bottle support remains locked until the roll 30 rides down an incline 39, (Fig. 7), on the track 29, thus restoring the block 32 to the influence of the spring 35 which again depresses the block 60 32 to cause the rolls to reengage the bars.

In order to return the bottle support to a position of clearance after the bottle thereon has been filled, the lower end of the plunger 5 is provided with a roll 40, (Fig. 65 7), which is engaged by an incline 41 upon the

bottom of the track 29. After the bottle support has been returned to its position of clearance the filled bottle is discharged from the support and an empty bottle loaded thereon while the support is in the position C, (Fig. 70 7). After the empty bottle is loaded on the support an incline 42 on the track 29 permits the spring 28 to again elevate the bottle mouth against the dog 17. As shown in Fig. 7, sufficient clearance is left between the 75 roll 40 and the bottom of the track 29 to permit the springs to elevate the bottle supports through variable distances depending upon the height of the bottles upon the supports.

At the discharging station, (Fig. 2), the bottles are loaded directly upon a runway 43, (Fig. 2), by the feeding means embodied in the filling mechanism. The runway has a width less than twice the width of a bottle and the 85 bottles therein are pushed by the last bottle loaded on the runway in a single file with each bottle in contact with the adjacent bottles until they are taken, one by one, from the runway by the feeding means embodied 90 in the capping mechanism which is substantially similar to the capping mechanism described in an application for Letters Patent of the United States filed by me February 24, 1913 Serial No. 750,289, and so this 95 mechanism need not be described in detail herein.

The carrier 2 for the bottle supports and filling heads is provided with a bevel gear 44, (Figs. 1 and 2), which is driven by a bevel gear 45, secured to one end of a horizontal shaft 46, journaled at one end in a bearing carried by the pedestal for the carrier 2 and at its other end in bearings carried by a housing 47 on the machine frame. As shown in Fig. 2, the filling and capping mechanisms are provided with thirty-two and four supports, respectively. In order to operate the filling and capping mechanisms in timed relation the shaft 46, 105 herein called the timing shaft, is driven so that it rotates thirty-two times for one complete revolution of the carrier 2 and four times for one complete rotation of the bottle support carrier of the capping mechanism. 110 By operating the filling and capping mechanisms in the manner described, the capping mechanism removes a filled bottle from the runway 43 simultaneously with the deposit of a filled bottle upon the runway by the filling mechanism. As the bottles are positively controlled from the time they enter the filling mechanism until they leave the capping mechanism all danger of the bottles accumulating at either end of the runway, 120 125 or any other place in the machine is obviated.

Secured near the end of the shaft 46, within the housing 47, is a disk 48, (Figs. 4 and 5), which is driven through a cou-

pling with a bevel gear 49 loosely mounted on the shaft 46. This coupling comprises a lever 50 pivoted on the face of the bevel gear next to the disk 48. One end of the lever 50 carries a roll 51 which is normally held against a shoulder 52, formed in the periphery of the disk 48, by a spring 53, coiled around a rod 54 one end of which is pivoted to the gear 49 and the other end of which loosely passes through a hole formed in the free end of the lever 50. The bevel gear 49 is driven by a bevel gear 55 which is fixedly mounted on a clutch-member 70, the clutch-member being mounted on, and fixed to, a shaft 57 which drives the capping mechanism, (Fig. 2). A sleeve 56, which is loosely mounted on the shaft 57, carries two gears 58 and 59, the gear 58 being larger than the gear 59. When the gear 58 is engaged by a pinion 60 carried by a change-gear shaft 61, which is driven from a motor pinion 62 through a gear 63 on the shaft 61, the carrier 2 is driven so that a quart bottle can be filled during one of its revolutions. When the sleeve 56 is driven by a gear 64 on the shaft 61 through the small gear 59 the carrier 2 is driven at a higher speed so that a pint bottle may be filled during a single rotation of the carrier. To shift the gears 60 and 64 the shaft 61 is provided with a sleeve 65 which is splined to the shaft and fixed to the gears 60 and 64. By sliding the sleeve on the shaft these gears may be engaged with the gears 58 and 59, respectively. Before shifting the sleeve 65, however, it is necessary to elevate a yoke 66 which loosely embraces the gears 61 and holds the shaft from sliding longitudinally when they are in mesh, (Figs. 4 and 5). The yoke 66 is formed on a rod 67, loosely mounted in the housing 47, which is provided with a knurled thumb nut 68 to facilitate the elevation of the yoke by the operator. The clutch-member 70 constitutes one member of a clutch of well known form, of which the other member (not shown) is formed integral with, or attached to, the sleeve 56, so that by the operation of the clutch the sleeve may be coupled both to the gear 55 and to the shaft 57, to cause the filling-mechanism and the capping-mechanism to be driven simultaneously. The clutch is operated in the usual manner by a dog 69, which is pivotally mounted on the clutch-member 70. The dog is actuated by the usual sleeve 71, which slides upon the shaft 57. This sleeve has a frusto-conical end, so that when the sleeve is moved from left to right, as shown in Figs. 4 and 5, the end of the dog is forced outwardly, thus throwing the clutch into operation, and so long as the dog remains in engagement with the cylindrical body of the sleeve the driving-connection is maintained. In order to

shift the sleeve 71 longitudinally on the shaft 57, the sleeve 71 carries a pair of pins 73 which are engaged by a pair of yokes 74 each formed on an arm 75 projecting from a rock shaft 76 journaled in the housing 47.

When the filling mechanism is operating properly, the disk 48 and the parts of the coupling connecting the disk 48 with the bevel gear 49 are retained in normal position by the spring 53. If the filling mechanism becomes jammed, or, for any other reason, causes an overload upon the driving connections sufficient to overcome the tension of the spring 53, the rotation of the disk 48 will cease and as the bevel gear 49 continues to rotate, the roll 51 will be disconnected or escape from the shoulder 52 of the disk 48 and travel around the periphery of the disk until it strikes against the upper end of an arm 77 which is connected by an arm 78 to the rock shaft 76. When the roll 51 engages the arm 77 the sleeve 71 is actuated in a direction to release the gear 55 from the shaft 57 and sleeve 56. With this construction the capping mechanism is stopped after the filling mechanism has stopped.

When the overload in the filling mechanism is removed by the proper attention to the mechanism the jamming or improper operation of which caused the throwing out of the driving mechanism the coupling between the disk 48 and the gear 49 may be reset and the initial timed operating relation of the filling and capping mechanism restored by slowly rotating the shaft 46 backward by means of a hand wheel 99 on the shaft until the roll 51 again snaps in place behind the shoulder 52.

While the mechanism for capping the bottles is constructed to perform the capping operation without liability of breaking the bottles it sometimes happens that a bottle which contains a hidden crack is passed into the machine and is broken during the capping operation. When this happens, sometimes a piece of the broken bottle remains upon the support at the time when the support is ready to receive one of the filled bottles from the transferring devices embodied in the capping mechanism. When the filled bottle is loaded on the support under such conditions its bottom rests upon the piece of glass which causes the bottle to tip at such an angle as to bring it outside of the range of the capping instrumentalities. Usually the bottle is knocked off the support and broken. The same trouble may be caused through the collection upon the bottle supports of the cork disks which sometimes drop out of the caps.

In order to prevent the continued loss of bottles and their contents caused by the piling up of broken glass or cork upon the

bottle supports the machine of the drawings is provided with mechanism for detecting the presence of the broken glass or cork upon the bottle supports and for stopping the machine in time to prevent further loss. To this end the capping mechanism frame supports a centrally pivoted arm 79, (Figs. 12 and 14), one end 80 of which is normally held in the path of movement of the empty bottle support 81 of the capping mechanism as it passes from the station where the capped bottles are discharged from the machine to the station where the filled bottles are received from the filling mechanism. The end 80 of the arm 79 is held normally forward, until a stop 82 on its other end engages a rotary disk 83, by a leaf spring 84 carried by the capping mechanism frame. The disk 83 is rotatably mounted upon a flat plate 84', (Figs. 14, 15 and 16), which is cut away at 85 to permit the rear end of the arm 79 to operate between the disk 83 and the top of the capping mechanism frame. The plate 84' is also cut away at 86 to expose a curved slot 87, (Figs. 12, 13, 14 and 16), formed in the top of the capping mechanism frame. The slot 87 gradually decreases in depth from the point 88, (Fig. 14), where it is deepest, to the point 89 where it merges with the top of the capping mechanism frame, (Fig. 13). The disk 83 is provided with four hollow posts 90 each of which contains a cylindrical rod 91. The disk 83 is continuously rotated during the operation of the capping mechanism at such a speed as to insure the radial registration of an empty bottle support 80 with one of the posts 90, (Figs. 12 and 14). As long as neither glass nor cork is deposited upon a bottle support the arm 79 will always be positioned at the time of the radial registration of the bottle support 80 and post 90 in the manner illustrated in Figs. 12 and 14. In this position a hooked end 92 on the arm 79 will prevent the rod 91 in the post 90 from dropping into the slot 87, (Figs. 14 and 16). If, however, glass or cork is deposited upon the bottle support 80, the arm 79 will be moved into a position like that shown in the dotted lines of Fig. 14 thus permitting the rod 91 to drop into the slot 87. When this happens, the rod 91 rides along the slot 87 and strikes the end of a slide 93, (Figs. 17 and 18), mounted to slide in ways formed in the top of the capping mechanism frame. The slide 93 is provided with a cam 94 which engages a block 95 formed on a link 96 pivoted to a second link 97, (Fig. 11), which is connected with an arm 98 projecting from the rock shaft 76, (Figs. 1, 3, 4, and 5). As shown in Fig. 18, a spring 105, attached to the left-hand end of the link 96, tends to draw it toward the left, but this movement is normally prevented by en-

gagement of the link with a stationary flange 106. When, however, the slide 93 is moved to the right, in the manner above described, the cam 94 acts to depress the link 96, by engagement with the block 95, thus swinging the link downwardly out of engagement with the flange 106; whereupon, the spring 105 pulls the link to the left. This movement, through the connections described, causes the rock-shaft 76 to be turned in such a direction that the drive-clutch is thrown out of operation. To reset the slide 93 in operative position the slide carries a knob 100, (Figs. 7 and 18), which may be grasped by the operative to facilitate the positioning of the slide.

Sometimes it is desirable to cap filled bottles which for some reason passed through the capping mechanism without being capped. In order to permit the placement of these filled bottles upon the runway 43 the shaft 46 is constructed in two parts, (Fig. 1), which are connected by a clutch 101 operated through a hand lever 102. When it is desired to place the filled bottles of the class hereinbefore referred to upon the runway the clutch 101 is thrown out thus permitting the capping mechanism to run and the filling mechanism to stop. When sufficient room for the filled bottles is prepared for them on the runway the bottles are placed thereon and the clutch thrown into again operate the filling and capping mechanisms. The clutch is of the well known one pin type the one pin of which is arranged to engage its co-operating member only when the filling and capping mechanisms are restored to their timed operating relation.

While the invention has been illustrated and described in connection with a machine for filling and capping bottles it will be apparent to those skilled in the art that many features of the invention are applicable to the other machines in the system of automatic machines devised by me for packaging liquids.

It will be clear to those skilled in this class of machines and with the general objects of the present invention in view, that the particular form of filling or capping mechanism employed is not essential and that changes may be made in the details of structure, the described and illustrated embodiment thereof being intended as an exploitation of its underlying essentials, the features whereof are definitely stated in their true scope in the claims herewith.

What is claimed as new, is:—

1. A filling and capping machine, having, in combination, mechanism for filling bottles, mechanism for capping the filled bottles, and means for stopping the filling and capping mechanisms under an over-load, said means permitting the capping

mechanism to continue to operate for an interval after the stopping of the filling mechanism, substantially as described.

2. A filling and capping machine, having, in combination, mechanism for filling bottles, mechanism for capping the filled bottles, a two part shaft having one part connected to the filling mechanism and the other part connected to the capping mechanism, and a clutch for connecting the parts of the shaft constructed and arranged to connect the parts of the shaft only in a predetermined position in which the shaft will operate the filling and capping mechanisms in timed relation, substantially as described.

3. A filling and capping machine, having, in combination, mechanism for filling bottles, mechanism for capping the filled bottles, a driving member therefor, a connection between the member and the filling mechanism comprising a coupling the parts of which are constructed to be disconnected under an overload, and means for throwing out the capping mechanism by the movement of one of the parts of the coupling after it is disconnected from the other part, substantially as described.

4. A filling and capping machine having, in combination, filling-means; capping-means; and driving-mechanism normally connecting and actuating both said means in timed relation, the driving-mechanism being constructed and arranged to yield,

upon the occurrence of an overload in the filling-means, and thereupon automatically to discontinue driving both of said means, and also to disconnect them from each other so that they may come independently to rest.

5. A filling and capping machine having, in combination, filling-means; capping-means; driving-mechanism connected with the capping-means for actuating the latter; and yielding connections, between the driving-mechanism and the filling-means, for actuating the latter, said connections being constructed and arranged to yield, upon the occurrence of an overload in the filling-means, during the continued actuation of the capping-means.

6. A filling and capping machine having, in combination, filling-means; capping-means; driving-mechanism normally connected with the capping-means for actuating the latter; yielding connections, between the driving mechanism and the filling-means, for actuating the latter, said connections being constructed and arranged to yield, upon the occurrence of an overload in the filling-means; and means for thereafter automatically disconnecting the driving-mechanism from the capping-means.
